UNITED STATES PATENT OFFICE.

FRANK R. DE FOY, OF DANNEMORA, NEW YORK, ASSIGNOR TO HIMSELF
AND C. H. STACKPOLE, OF SAME PLACE.

GAME-TABLE.

SPECIFICATION forming part of Letters Patent No. 296,280, dated April 1, 1884.

Application filed November 14, 1883. (No model.)

To all whom it may concern:

Be it known that I, FRANK R. DE FOY, of Dannemora, in the county of Clinton and State of New York, have invented a new and Improved Game-Table, of which the following is a full, clear, and exact description.

Reference is to be had to the accompanying drawings, forming part of this specification, in which similar letters of reference indicate corresponding parts in both figures.

Figure 1 is a plan view of my new game-table, and Fig. 2 is a sectional elevation of the same.

The invention will first be described in connection with the drawings, and then pointed out in the claims.

In the drawings, A represents the table, supported upon the legs B B. The table A is rectangular in form and covered with baize a, and is cushioned at the edges, as shown at C C, like an ordinary billiard-table. At the head of the table, near the corners, are formed the pockets b b, which are marked "25" or any other desired number; and a little beyond the center of the length of the table, toward its head, and in the center of the width of the table, is formed the circular cluster of pockets c c, each of which pockets is made of hard rubber with flanges c', and set in a circular countersunk 25 recess, c", made in the table, as shown in Fig. 2, the flanges c' serving to hold the baize a at the openings c"; and these pockets c are all numbered as shown in Fig. 1. Just beyond the cluster of pockets c, toward the head of the table, are secured across the table in crescent form the uprights, d d, five in number, and just beyond these uprights are formed through the table the slots e e, in which are pivoted the levers g g. In the uprights d d are 30 fitted the headed buffers f f. Upon these buffers, between the heads f' f' thereof and the uprights, are placed the coiled springs f' f', and at their rear ends these buffers f f are attached to the upper ends of the levers g g; and to the lower ends of these levers g g are attached the hammers g' g', which stand in front of the gongs h h, secured under the table, so that when any of the buffers f f are struck by a ball in playing the game, as hereinafter described, a gong

will be sounded. In the center of the table is 50 pivoted, in the circular opening i, the wheel D, which has secured to its upper side, equidistant apart, the pegs E E E. In its center this wheel D is formed with the spot j, and leading from this spot is the radial index-line k, 55 and around the wheel D are formed upon the baize a of the table, equidistant apart, the radial lines l l, six in number, which are numbered as shown in Fig. 1, and count, in playing the game, as numbered when the index k 60 stops coincident with them.

In playing the game, which I call "Apollo," nine balls are used—four white, four black, and one red—and either two or four persons may join in the game. The red ball is the 65 spot-ball, which is first placed on the spot j in the center of the revolving wheel D, where the ball is guarded by the pegs E. The first player now shoots a ball, with a cue, from the foot of the table, at one of the guards or pegs 70 E, so as to revolve the wheel D and start the red ball off from the said wheel. If the red ball goes in any of the pockets c it is to count for double the number marked upon such pocket; and when turning, if the index-line k 75 of wheel D stops in line with one of the radial lines l on the table, it will count for whatever such line is marked. The second and all subsequent players will shoot at the balls on the 80 table, and if they strike the red ball and any other ball it will count five; and if the player sends any of the balls in the pockets c, or strikes a buffer, f, it will count whatever they are marked. If the player happens to send his own ball in one of the corner pockets, b, 85 it counts twenty-five for his opponent. The player does not score any points unless he touches, with the ball he shoots, his partner's ball, which makes the game very interesting; and the game is difficult, since the playing is 90 from one end of the table only. Ordinarily the game will be for two hundred points. To make the red ball count, the player's ball must be touched first. If the player, after touching his partner's ball, touches the red ball, it 95 will count five for the player's ball and ten for the red ball, making a total of fifteen. In this manner the game, besides being very interest-

ing and difficult, is very amusing and requires a good deal of skill, and it affords considerable exercise.

Having thus described my invention, I claim as new and desire to secure by Letters Patent—

- 5 1. The game-table herein shown and described, formed with the central revolving wheel, D, cluster of pockets e, spring-buffers f, and corner pockets, b, the spring-buffers being attached to gong-levers g, and the wheel D, provided with pegs E, and index-line k, and surrounded by the radial numbered lines l, substantially as set forth.
- 10 2. In a game-table, the revolving wheel D, having the guard-pegs E, substantially as and for the purposes described.
- 15 3. In a game-table, the cluster of pockets e, arranged beyond the wheel D that has pegs E, substantially as set forth.
- 20 4. In a game-table, the spring-buffers f, arranged on the surface of the table beyond the revolving wheel E, substantially as set forth.
- 25 5. In a game-table, the combination, with the

spring-buffers f, of the levers g, and gongs h, arranged substantially as described.

25

6. In a game-table, the series of spring-buffers f, arranged beyond the cluster of pockets e, substantially as set forth.

7. In a game-table, the series of spring-buffers arranged beyond the cluster of pockets e 30 and beyond the wheel D that has the guard-pegs E, substantially as set forth.

8. In a game-table, the wheel D, provided with pegs E, and index-mark k, in combination with the radial marks l, substantially as 35 set forth.

9. In a game-table, the pockets e, made of hard rubber, with flange e', set in a counter-sunk recess, e'', for forming the pocket and at the same time holding the baize a around the 40 recess at opening e'', substantially as shown and described.

FRANK R. DE FOY.
